LATCH MECHANISM

Joseph Pickles, Dearborn, Mich., assignor to Ferro Stamping Company, Detroit, Mich., a corporation of Michigan

Application February 7, 1955, Serial No. 486,477

4 Claims. (Cl. 292—280)

The present invention relates to latch mechanism and more particularly, to latch mechanism including an automatic take-up device to maintain a tight latched relation at all times.

It is an object of the present invention to provide latch mechanism of the type having a latch rotor rotatable in one direction into latched position, and rotatable in the opposite direction out of latched position, in combination with releasable means normally preventing rotation of the rotor out of latched position.

More specifically, it is an object of the present invention to provide latch mechanism including a latch rotor having a plurality of lobes thereon, a stationary abutment adjacent the latch rotor, and wedge cam means movable into and out of the space between the lobes on the rotor and the abutment to prevent rotation of the rotor in unlatching direction.

It is a further object of the present invention to provide mechanism as defined in the preceding paragraph in which the lobes and wedge cam means are constructed and arranged such that rotation of the rotor towards latched position operates to move the wedge cam out of the space between the lobes of the rotor and the abutment.

It is a further object of the present invention to provide latch mechanism comprising a rotary latch having inclined or helically extending latching teeth in combination with a striker plate having a laterally open recess provided at one side thereof with one or more inclined projections substantially conjugate to the inclined teeth on the rotor.

Other objects and features of the invention will become apparent as the description proceeds, especially when taken in conjunction with the accompanying drawings, wherein:

Figure 1 is an end elevational view of the latch mechanism.

Figure 2 is a side elevational view of the structure shown in Figure 1, looking to the left in Figure 1.

Figure 3 is a fragmentary side elevational view of the structure shown in Figure 1, looking at the right in Figure 1.

Figure 4 is a plan view of the structure shown in Figure 1.

Figure 5 is a diagrammatic view showing the relationship of the lobes and wedge cam.

Figure 6 is a fragmentary elevational view showing the relationship between the latching rotor and keeper.

Figure 7 is a fragmentary sectional view on the line 7—7, Figure 6, showing the relationship between helical inclined latching teeth on the rotor and correspondingly inclined teeth on the keeper.

The latch mechanism to which the present invention relates is of the type having a latching rotor indicated generally at 10 having a plurality of latch teeth 12 which may conveniently be in the form of substantially involute gear teeth. The latch mechanism includes a partial housing 14 and this housing and the latch teeth 12 of the rotor

2

coact to firmly support a door or other closure in the manner best illustrated in Figure 6. In this figure there is illustrated a keeper 16 having a recess 18 therein provided with a smooth slightly upwardly inclined bottom wall 20 and having its upper surface to provide projections 22 which are generally equivalent to rack teeth conjugate to the generally involute teeth of the rotor 10. The housing 14 is shaped with an edge wall portion 24 to fit against the inner wall 26 of the recess 18.

In practical use the latch mechanism including the rotor 10 is preferably supported at the edge of a door with the axis of the rotor 10 extending in the plane of the door. The keeper plate 16 is mounted at the edge of the door opening in position to receive the tooth portion of the rotor 10. Due to the upward inclination of the bottom wall 20, the door is firmly supported at its free edge and is retained in firmly latched relation by the provision of releasable means normally preventing rotation of the latch rotor out of the latched position illustrated in Figure 6.

It will be understood of course that the rotor 10 is provided for rotation in one direction during movement into latched position and for rotation in the opposite direction during movement out of latched position.

In order to retain the door latched, releasable means are provided preventing rotation of the latch member in the direction required to accompany movement of the latch out of the latched position. In accordance with the present invention this releasable means is movable so as to take up slight additional increments of rotation of the rotor toward latched position, and so to maintain the latch always firmly supported against opening movement. It is desired to emphasize that the present latch mechanism is operable to prevent opening movement of a door from a partially latched position and will take up so as to prevent slight opening movement of the door from further closed positions thereof.

The releasable mechanism for preventing rotation of the rotor toward unlatched position comprises a plurality of lobes 30 which are axially spaced from the teeth 12 of the rotor. The lobes 30 may be formed as an integral part of a unitary body including the teeth 12, or they may be separately formed and rigidly attached thereto. In the specific embodiment of the invention illustrated the latch rotor 10 is shown as provided with six involute latching teeth and as provided with three of the lobes which coact with other mechanism to prevent rotation of the latch toward unlatched position.

Reference is now made to Figure 5 which shows diagrammatically the relationship of parts entering into the retention of the rotor in latched position. As seen in this figure the lobes 30 each include surfaces 32 which preferably are constant rise cam surfaces, or in other words, involute surfaces of a base circle concentric with the axis of the rotor 10. The opposite sides 34 of the lobes are differently shaped for a purpose which will subsequently appear.

Associated with the lobes 30 of the rotor is a wedge cam element 40 including an arm portion 42 and a wedge cam portion 44, the surface 46 of which is preferably also a constant rise cam surface or involute in profile.

The arm 42 is provided with an elongated opening 48 receiving a pin 50 which connects the arm 42 for rocking movement about the pin 50 but with provision for bodily movement longitudinally of the elongated slot 48.

The arm 42 is provided with an arcuate slot 52 having a generally arcuate surface 54 engageable with a fixed abutment pin 56. Since the surface 54 is arcuate and the surface 46 is generally involute, these two surfaces converge and define therebetween the equivalent of a wedge interposed between the camming surface 32 of a lobe 30 and the fixed abutment 56.

From an inspection of Figure 5 it will be apparent that the wedge portion 44 of the element 40 is effective to prevent counterclockwise rotation of the rotor 10. It will also be apparent that forces tending to rotate the rotor 10 counterclockwise produce camming forces tending to swing the wedge cam element 40 in a counterclockwise direction. However, such movement of the wedge cam element 40 is frictionally opposed by the friction between the fixed abutment 56 and the arcuate surface 54, as well as the frictional forces existing between the lobe surface 32 and the camming surface 46 of the wedge cam element 40. Since both of these frictional forces oppose camming of the wedge cam element 40 in a direction to release the rotor 10, it will be apparent that the included angle between the surfaces 46 and 54 considered as a wedge may have a value substantially twice as great as the angle of repose for the materials of which the abutment 56, surface 54, surface 46, and surface 32 are formed. This permits a relatively great cam rise on the cam surface 46 for a correspondingly small angular movement of the arm 42.

As previously indicated, the surface 34 of the lobe is shaped differently from the involute side 32 thereof. The wedge cam device 40 is provided with a surface portion 58 cooperable with the side 34 and particularly the tip 60 of the lobes so that upon rotation of the rotor 10 in the direction resulting from movement of the lobe into latched position, the lobe rocks the wedge cam element 40 out of latching position.

By properly selecting the angular orientation of the lobes 30 with reference to the teeth 12, an arrangement results in which the latch rotor 10 cams the wedge cam device out of blocking position as the teeth 12 roll over the teeth 22 of the keeper until the housing 14 reaches the position illustrated in Figure 6. If the door is not completely closed so that the wall portion 24 of the housing is spaced from the end wall 26 of the recess in the keeper, the latch will operate to prevent opening movement of the door. If the door is thereafter caused to move by small increments, such for example as by vibration, further toward fully closed position, suitable spring means bearing against the wedge cam device 40 cause it to follow up so as to prevent return motion of the latch rotor from the furthest latched position which it reaches.

Referring now to a practical embodiment of the invention, the construction comprises an angular support plate 62 having a wall 64 normally disposed at the free edge of a door, and a wall 66 disposed at one side of the door. Where the latch mechanism is used in conjunction with an automobile, the wall 66 is normally located at the inner surface of the door. The wall 64 includes a rearwardly extending flange portion 68 to which is secured suitable lock mechanism indicated generally at 70 and includes an actuator 72 for release of the latch as will subsequently appear.

The toothed portion of the latch rotor including the teeth 12 is partially housed within the housing 14 previously referred to, which housing includes a mounting flange 74 welded or otherwise secured as indicated at 76 to the outer surface of the plate 64. At the opposite side of the plate 64 from the toothed portion of the rotor 10 is provided the lobe portion thereof having the lobes 30, as best seen in Figure 1. Mounted in the plane of the portion of the rotor containing the lobes 30 is a lever or arm 78, this arm being mounted for rotation about a pin 80 and including an enlarged opening providing for some freedom of movement of the arm 78 in a direction perpendicular to the axis of the pin 80. The arm 78 is provided with an arcuate slot 82 through which extends a fixed abutment pin 84. A spring 86 is provided surrounding the pin 80 and includes an end portion 88 engageable with a laterally bent flange 90 on the arm 78. With the parts in the position illustrated in Figure 1, it will be apparent that rotation of the lobes 30 in a

clockwise direction is prevented by the wedge action of the portion of the lever intermediate the lobe 30 and the fixed abutment 84. The camming surface 92 of the arm 78 engages the involute surface 94 of the lobe 30.

In order to free the rotor 10 for the free rotation required to move the door to open position, the arm 78 is rocked in a clockwise direction, as seen in Figure 1 for example by pressure applied against the flange 90. In the practical door construction the flange 90 may be engaged by suitable actuating means such as a handle controlled lever or push button at the outside of the door.

The spring 88 is effective to cause the camming surface 92 of the wedge cam element 78 to follow up any movement of the lobes 30 of the rotor.

As is customary in automobile door latches, additional means are provided for actuating the latch release mechanism. This means comprises an actuating lever 100 pivoted to the plate 66 as indicated at 102. The lever 100 includes a projection 104 movable into the path of a hook shaped portion 106 on the wedge cam arm 78 so as to block movement of the arm 78 to latch release position. The lever 100 is provided with an opening 108 receiving one end of the key actuated crank 72. The lever 100 includes a projecting arm 110 which overlies the hook portion 106 of the wedge cam arm 78 so that the wedge cam arm 78 may be moved to latch release position by swinging movement of the actuating lever 100. The lever 100 includes the elongated slot 112 for connection with the usual push button actuator provided on automobile doors, by means of which the lever 100 may be moved into and out of position to block release movement of the wedge cam arm 78.

From the foregoing description it will be apparent that when mounted on the edge of a door as previously indicated for coaction with the keeper plate as indicated in Figure 6, the door may be slammed shut which will result in rotation of the latch teeth 12 relative to the stationary rack teeth 22 of the keeper plate. This rotation of the latch rotor 10 automatically shifts the wedge cam arm 78 out of wedging position, but the wedge cam arm moves back to wedging position under the influence of the spring 86 as soon as the door is closed. The wedging action of the wedge cam arm prevents any slight reverse rotation of the latching teeth and since the spring continues to urge the wedge cam arm in wedging direction, it will follow up any further additional incremental movements in rotation of the latching teeth if the door moves slightly further toward latched position. In order to open the door it is necessary to release the wedge cam arm and this may be accomplished by swinging the wedge cam arm 78 in clockwise direction, as seen in Figure 1. This may be accomplished by pressing on the flange 90 of the arm through suitable outside handle mechanism or by inside remote control handle mechanism coupled to an opening indicated at 114 in the lever 100.

Referring now to Figures 6 and 7 there is illustrated an arrangement in which the latching teeth 12 are helical and are associated with inclined teeth 22 on the keeper plate 16. As best illustrated in Figure 7, one of the teeth 12 engages the innermost tooth 22 of the keeper plate. It will be appreciated that for the door to move toward unlatched position will require movement of the latch rotor having the latched tooth 12 in the direction of the arrow designated at 116, which movement is of course prevented since rotation of the rotor is prevented by the wedge cam device previously described. However, it will further be observed that due to the inclined relationship of the latch teeth 12 and the engaged tooth 22 of the keeper, movement of the tooth 12 (and hence of the entire latch mechanism) relative to the keeper in the direction of the arrows 118 is effectively prevented. As a result of this construction the inter-engagement between the latching teeth of the latch rotor and keeper provides a firm connection between the door and frame of

the vehicle longitudinally of the vehicle. As a result of this the door becomes a structural part of the vehicle frame.

The exact helix angle of the teeth 12 or angularity of the teeth 22 is not critical except that in order to retain a firm and effective engagement, the angle should be substantial. It will of course be apparent that if the teeth 12 of the latch rotor have a helix angle of zero degrees, they will have no effect whatever tending to cause the door to take up longitudinal stresses, but will be perfectly effective to retain the door in latched position. At the other extreme, the helix angle of the teeth cannot be too large since closing movement of the door is required to produce rotation of the latch rotor. For practical purposes the helix angle of the teeth 12 on the rotor will normally be between 30 degrees and 60 degrees. It will of course be apparent that the hand of the teeth 12 and the direction of inclination of the teeth 22 are required to conform and will be in the direction such that engagement between a single tooth 12 and a single tooth 22 is effective to oppose both opening movement of the door and longitudinal separation between the free edge of the door and the adjacent portion of the door opening.

The drawings and the foregoing specification constitute a description of the improved latch mechanism in such full, clear, concise and exact terms as to enable any person skilled in the art to practice the invention, the scope of which is indicated by the appended claims.

What I claim as my invention is:

1. Door latch mechanism for connecting the free edge of a swinging door and a door frame in which the door is pivotally mounted comprising a cooperating rotor and keeper releasably connecting the free edge of the door and the frame and including means for selectively preventing rotation of the rotor in the direction required to permit opening movement of the door from latched position, said rotor being disposed with its axis generally parallel to the plane of the door when the door is closed, said keeper comprising means defining a generally horizontal recess extending in a direction transverse to the plane of the door when the door is closed and having upper and lower surfaces, said recess being open at one end to receive said rotor and closed at its other end to provide an abutment surface, said keeper having in said recess a fixed locking projection, said rotor having a housing having a generally horizontal wall engaging one of said upper and lower surfaces of the recess in said keeper and having at one side of the rotor a surface engageable with the abutment surface of the recess in said keeper to limit closing movement of the door, said rotor having a radially extending locking projection movable over and engageable with the side of said fixed locking projection at the closed inner end of said recess, the pairs of engaging surfaces consisting of the engaging surfaces of said locking projections, and the engaging surfaces of said keeper at the closed inner end of its recess and the surface of said rotor housing at the side of said rotor, converging toward the free edge of the door to prevent separation between the free edge of the door and the adjacent edge of the door frame in a direction parallel to the plane of the door when closed.

2. Door latch mechanism for connecting the free edge of a swinging door and a door frame in which the door is pivotally mounted comprising a cooperating rotor and keeper releasably connecting the free edge of the door and the frame and including means for selectively preventing rotation of the rotor in the direction required to permit opening movement of the door from latched position, said rotor being disposed with its axis generally parallel to the plane of the door when the door is closed, said keeper comprising means defining a generally horizontal recess extending in a direction transverse to the plane of the door when the door is closed and having a pair of vertically separated surfaces one of which is smooth and

smooth and one of which includes a fixed locking projection, said recess being open at one end to receive said rotor and closed at its other end to provide an abutment surface, a housing partially covering said rotor and having a first wall providing a surface slideable over the smooth surface of said keeper and a second wall providing an abutment surface engageable with the abutment surface of said recess to limit closing movement of the door, said rotor having a radially extending locking projection movable over and engageable with the side of said fixed locking projection at the closed inner end of said recess, the pairs of engaging surfaces consisting of the engaging surfaces of said locking projections, and the engaging surfaces of said keeper at the closed inner end of its recess and the surface of said rotor housing at the side of said rotor, converging toward the free edge of the door to prevent separation between the free edge of the door and the adjacent edge of the door frame in a direction parallel to the plane of the door when closed.

20 3. Door latch mechanism for connecting the free edge of a swinging door and a door frame in which the door is pivotally mounted comprising a cooperating rotor and keeper releasably connecting the free edge of the door and the frame and including means for selectively preventing rotation of the rotor in the direction required to permit opening movement of the door from latched position, said rotor being disposed with its axis generally parallel to the plane of the door when the door is closed, said keeper comprising means defining a generally horizontal recess extending in a direction transverse to the plane of the door when the door is closed and having a pair of vertically separated surfaces one of which is smooth and one of which includes a plurality of fixed locking projections generally in the form of rack teeth, said recess being open at one end to receive said rotor and closed at its other end to provide an abutment surface, a housing partially covering said rotor and having a first wall providing a surface slideable over the smooth surface of said keeper and a second wall providing an abutment surface engageable with the abutment surface of said recess to limit closing movement of the door, said rotor having radially extending locking projections movable over and engageable with the side of said fixed locking projections at the closed inner end of said recess, the pairs of engaging surfaces consisting of the engaging surfaces of said locking projections, and the engaging surfaces of said keeper at the closed inner end of its recess and the surface of said rotor housing at the side of said rotor, converging toward the free edge of the door to prevent separation between the free edge of the door and the adjacent edge of the door frame in a direction parallel to the plane of the door when closed.

4. Door latch mechanism for connecting the free edge of a swinging door and a door frame in which the door is pivotally mounted comprising a cooperating rotor and keeper releasably connecting the free edge of the door and the frame and including means for selectively preventing rotation of the rotor in the direction required to permit opening movement of the door from latched position, said rotor being disposed with its axis generally parallel to the plane of the door when the door is closed, said keeper comprising means defining a generally horizontal recess extending in a direction transverse to the plane of the door when the door is closed and having upper and lower surfaces, said recess being open at one end to receive said rotor, abutment means acting between said door and door frame and having abutment surfaces disposed generally parallel to the plane of the door when the door is closed, said keeper having in said recess a fixed locking projection, said rotor having a housing having a generally horizontal wall engaging one of said upper and lower surfaces of the recess in said keeper, said rotor having a radially extending locking projection movable over and

engageable with the side of said fixed locking projection at the inner end of said recess, the pairs of engaging surfaces consisting of the engaging surfaces of said locking projections and the abutment surfaces of said abutment means converging toward the free edge of the door to provide wedge means operable to prevent separation between the free edge of the door and the adjacent edge of the door frame in a direction parallel to the plane of the door when closed, and manually releasable take-up mechanism operatively connected to said rotor and operable to prevent unlatching rotation thereof from any position within a range of door-latched positions as determined by engagement between the abutment surfaces of said abutment means.
